UNITED STATES PATENT OFFICE

2,335,306

DEVICE FOR PRODUCING HOMOGENEOUS MATERIAL

Fred Forrest Pease, Squantum, Mass., assignor to
Lever Brothers Company, Cambridge, Mass., a
corporation of Maine

Application November 29, 1941, Serial No. 421,048

14 Claims. (Cl. 259—6)

This invention relates to devices for producing homogeneous products, and relates particularly to suitable apparatus for working plastic masses of the type disclosed in my United States Patent No. 2,048,286 dated July 21, 1936. Apparatus of this type may be utilized to treat a plastic mass to convert it into a mass of marshmallowy consistency containing finely divided and uniformly dispersed bubbles of air.

The present invention relates particularly to apparatus by means of which closely controlled pressures and temperatures can be maintained automatically in the treatment of plastic masses, of the type described in the Pease patent and in particular masses of the type of soap, with the result that a product of high and uniform quality is obtained.

A suitable apparatus embodying the present invention may include a mechanism for feeding a material into an agitating zone at a constant pressure and rate where the material may be heated or cooled and agitated, as desired, and means for delivering the product from the agitating zone at a constant rate and under a uniform pressure so that operating conditions in the apparatus may be closely controlled to produce a uniform, homogeneous product.

More particularly, the feeding device may include a feed hopper and pump having impellers actuated by a torque-responsive, variable speed transmission which drives the impellers to feed the material at a constant rate.

Moreover, the agitating and aerating zone may be provided with a discharge mechanism or control head which controls the rate of discharge of the product and maintains a constant uniform back pressure against the product undergoing treatment, and discharges the product at a constant pressure.

Inasmuch as charging stock is fed into the treating device under uniform pressure and at a constant rate, and the treated mass is released from it at a constant pressure and rate, the mass is worked under uniform conditions of flow and pressure. This uniformity of treating conditions gives the most desirable results, particularly in the treatment of soap masses to produce an aerated soap.

For a better understanding of the present invention, reference may be had to the accompanying drawings in which:

Fig. 1 is a view in side elevation of a typical form of device embodying the present invention;

Fig. 2 is a view in section taken on line 2—2 of Fig. 1;

Fig. 3 is an enlarged view shown partly in section and partly broken away of the details of the ratchet transmission for the feeding device;

Fig. 4 is a view in section taken on line 4—4 of Fig. 1;

Fig. 5 is a plan view of the control head and discharge mechanism for the device, and

Fig. 6 is a view in section taken on line 6—6 of Fig. 5.

The form of the invention illustrated in the drawings includes an apparatus A of the type disclosed in my United States Patent No. 2,048-286 for Agitating, working, and conveying a plastic, fluid or semi-fluid mass to convert it into a product of marshmallowy consistency, as more particularly described in the aforesaid Patent No. 2,048,286. The invention will be described with reference to soap as the plastic mass, but it will be understood that other products can be treated with the apparatus as indicated in my Patent No. 2,048,286.

The device A includes generally a pair of intermeshing screw members 1a and 1b which are enclosed within a jacket 2 to which may be supplied a heating or a cooling fluid. The screw members 1a and 1b are mounted on shafts 3a and 3b which are journaled in the jacket 2 and which are provided with suitable non-meshing gears 4a and 4b.

The screws 1a and 1b may be driven by means of a motor 5 through a speed reduction gearing 6, sprocket 7, a chain 8, and a sprocket 9 which is fixed to a shaft 10 having a gear 11 thereon that meshes with the gears 4a and 4b and causes them to rotate in the same direction so that a mass of plastic, solid or semi-solid soap within the jacket 2 will be subjected to a kneading, shearing, agitating and conveying action for moving the soap mass from the left hand end of the jacket to the right hand end thereof, as viewed in Fig. 1.

The present invention includes a mechanism B for feeding soap stock to the device A at a constant rate and pressure, and a control head and discharge means C at the outlet from the device A which maintains a constant uniform back pressure against the mass undergoing working and agitation in the device A, as well as maintaining a constant uniform flow or discharge of the marshmallowy soap product from the device A. The described mechanism automatically maintains the pressure exerted on the soap mass at a constant uniform level and thereby assures that

the temperature and physical characteristics of the soap mass undergoing treatment will likewise remain uniform.

Referring to Figs. 1 and 4, the constant pressure feeding mechanism B includes a hopper 12 into which soap stock in a chip or flake form and having a predetermined moisture content is fed. Beneath, and communicating with, the hopper 12 is a feeding mechanism 13 comprising a housing 14 in which are rotatably mounted a pair of rotary pump impellers 15a and 15b. The impellers 15a and 15b receive the soap chips or flakes from the hopper 12 and feed them into the jacket 2 where they are received by the screws 1a and 1b and fed and worked during their passage through the device A. The pump impellers 15a and 15b are mounted on suitable shafts 16a and 16b which are provided with intermeshing gears 17a and 17b as shown in Figs. 1 and 2.

The shaft 16a is provided with a plurality of ratchets 18a, 18b, 18c, and 18d, which are fixed thereto and are driven by means of a pawl mechanism.

As shown in Fig. 3, the pawl mechanism includes a rocker member 19 for each ratchet which is rockably supported upon the shaft 16. Each rocker member 19 includes two plates 19a and 19b disposed on opposite sides of the corresponding ratchet and which have pivotally mounted therebetween a plurality of pawls 20a, 20b and 20c, which are urged by means of springs 21 against the teeth of the ratchet wheel 18a, 18b, 18c, or 18d. Thus, upon rocking movement of the pawl carrier 19 in a clockwise direction, as viewed in Fig. 3, the ratchet 18d will be rotated in a clockwise direction. Upon counter-clockwise motion of the pawl carrier 19, the pawls will slide over the teeth of the ratchet 18d.

The several pawl carriers 19 cooperating with the ratchets 18a, 18b, 18c and 18d, are driven by means of connecting rods 22a, 22b, 22c and 22d provided with eccentric straps 23a, 23b, 23c and 23d which receive the eccentrics 24, these eccentrics being staggered angularly with relationship to each other so that the action of the various pawl carriers 19 in rotating the shaft 16a is successive, thereby causing almost continuous rotation of the shaft 16a and the impellers 15a and 15b.

Inasmuch as the soap stock may be in chip, pellet or flake form, difficulty is encountered in feeding a constant volume of the stock into the device A when a continuous unvarying drive for the impellers 15a and 15b is provided. The reason is that the pieces comprising the mass being charged may vary in size and in the amount of their compacting. The amount of air or free space within the mass may vary. Accordingly, a torque-responsive, variable speed transmission is provided for driving the impellers 15a and 15b and for varying the speed of rotation and the pumping action of the impellers 15a and 15b so as to feed the stock at a uniform pressure and rate into the device A. This mechanism consists of a resilient coupling between the rocker members 19 and the respective connecting rods 22a, 22b, 22c and 22d. Referring particularly to Figs. 1 to 3, the resilient connection includes a yoke 25a, 25b, 25c and 25d, pivotally mounted between the plates 19a and 19b of each rocker member 19 which slidably receive the respective connecting rods 22a, 22b, 22c and 22d. Each of these connecting rods, for example connecting rod 22d (Fig. 3), is provided with a fixed collar 26 thereon which engages the yoke 25d to rock the pawl carrier 19

in a counter-clockwise direction. The yokes 25a to 25d are normally urged toward the collars 26 by means of the coil springs 27a, 27b, 27c or 27d encircling the corresponding connecting rods.

5 The springs 25a to 25d are retained under compression by means of the washers 28a, 28b, 28c or 28d, and the pairs of lock nuts 29a, 29b, 29c or 29d on the threaded upper ends of the respective connecting rods.

10 When the pressure exerted by the impellers 15a and 15b exceeds a predetermined maximum pressure and the rate of feed exceeds the rate at which the mass is conveyed through the device A, the springs 27a, 27b, 27c, 27d, may give slightly thereby rotating the impellers through a shorter angular distance and decreasing the speed of rotation of the impellers until the abnormal pressure and rate of feed no longer exist.

15 In operation, as the soap stock is forced by the impellers 15a and 15b into the jacket 2, the pawl carriers will be rocked distances which are substantially inversely proportional to the pressure generated by the impellers. Therefore, the impellers 15a and 15b are displaced angularly about their axes of rotation by each pawl and ratchet mechanism such distances as to maintain a uniform constant pressure within the jacket 2 of the device A and a uniform rate of feed.

20 Preferably the impellers 15a and 15b are adjusted to feed the soap somewhat more rapidly than the device A can convey it away. Any suitable mechanism for maintaining this slightly higher rate of feed may be used. The mechanism illustrated consists of a sprocket 30 fixed to the shaft 16 which, by means of a chain 31 and a sprocket 32, drives the eccentric shaft 33. The impellers act to force the feed forward on their outside arcs of movement and may permit the soap mass to leak back between them on their inside arcs of movement if there is sufficient back pressure as a result of the soap not being conveyed away by the device A.

25 The present invention includes a discharge mechanism or control head C which not only assists in the control of pressure but also may be utilized to reduce to a minimum turbulent or induced flow within the soap mass prior to the release of the molten mass to a form-imparting device.

30 Referring to Figs. 5 and 6, the control head C, is shown as receiving the soap as it issues from the device A. The illustrated control head C includes a T-shaped coupling 35 having flanges 35a and 35b at its opposite ends. The flange 35a is connected in any suitable way to a flanged outlet 36 on the end of the jacket 2 of the treating device A. Within and extending axially of the coupling 35 are a pair of relatively rotatable telescoped tubular valve plug sleeves 37 and 38. The outermost sleeve 37 is provided with a port 39 which may be rotated into alignment with an escape port 40 in the bottom of the T-coupling 35 or with the right angularly related discharge branch 41 of the coupling 35. The innermost sleeve 38 is provided with an elongated transversely tapered slot 38a extending around the sleeve for about 160°. This slot 38a may be adjusted relatively to the port 39 to regulate the rate of flow of the soap mass through the port 39. 35 The two sleeves 37 and 38 are provided with actuating handles 42 and 43 which permit them to be rotated so that the soap mass issuing from the device A may be directed either through the branch 41 or downwardly through the escape port 40. Suitable dial plates and indicators may be

mounted on the sleeves 37 and 38, if desired, to indicate the angular relationship of the sleeves. This arrangement is extremely advantageous inasmuch as it permits regulation of the flow of the soap mass and observation of the characteristics of the soap mass with the flow of the soap through the escape port 40, until the soap has attained the desired characteristics. After the soap mass has attained the desired characteristics and the desired rate of flow is obtained, the sleeves 37 and 38 may be swung in their relatively adjusted positions into alignment with the discharge branch 41 so that the soap can be discharged for further treatment.

The sleeve 37 is retained in axially fixed position by means of a collar 37a thereon. This collar is retained in a recess 35c in the exterior surface of the flange 35b of the coupling 35 by means of a cover plate 35d which is fixed to the flange 35b. The sleeve 38 has a shoulder 38b thereon which abuts against a shoulder 37b in the interior of the sleeve 37 thereby preventing outward movement of the sleeve 38.

The branch 41 of the coupling 35 has a diverging passageway 45 therein having its larger end in communication with a movable conduit 46 of generally rectangular cross-section. The diverging passageway 45 permits the soap to expand gradually to fill and flow along the conduit 46.

The conduit 46 may be formed of suitably reinforced sheet metal and has one end fixed between an exterior frame 47 and inner member 48 having an aperture 48a therein which forms the diverging continuation of the passageway 45. A flanged end portion 48b in the member 48 abuts the end of the conduit 46 and engages the frame 47. The frame 47 and the member 48 may be secured to each other in any suitable way, such as by welding. The frame 47 is provided with outwardly projecting ears 49 and 49a for receiving loosely the stud bolts 50 and 51 which are fixed in a flange 52 on the end of the branch 41. Springs 53 are mounted on the stud bolts 50 and 51 and bear against the ears 49 and 49a to force the conduit 46 and its end members 47 and 48 against the end of the branch 41 to return them in leak-proof relation, but permitting relative movement therebetween. Preferably a rubber gasket 54 is mounted between a boss 55 of reduced area on the member 48 and in a recess 56 in the end of the branch 41 to prevent leakage while permitting relative movement between the conduit 46 and the branch 41.

Any tendency for the soap mass to stick in the conduit 46, as a result of the reduction of pressure and the formation of a skin thereon, for example, as a result of slight cooling, may be overcome by vibrating the conduit 46. The member 48 on the conduit 46 is provided with an extension 57 which supports an air hammer 58 of conventional construction including a reciprocating piston (not shown).

The pressure exerted on the soap mass in the passageway 45 and within the device A may be controlled by a pressure release device comprising a generally dome-shaped valve plug 59 which is resiliently urged into a pressure release port 60 in the under side of the branch 41. A "Sylphon" bellows 61 is mounted on the coupling 35. The bellows has a projecting pin 62 thereon which bears against an adjustable set screw 63 in a lever 64. The lever 64 is pinned to a shaft 65 which is rotatably mounted between the flanges 35a and 35b of the T-coupling 35. The shaft 65 also has fixed to it an arcuate arm 66

having the valve plug 59 on its end. By maintaining a uniform fluid pressure within the "Sylphon" bellows 61, the valve plug 59 is forced into the pressure release port 60 with uniform pressure. So long as the pressure on the soap in the discharge branch 41 does not exceed the pressure exerted on the valve plug 59, the latter will not leave the port 60. However, when the pressure on the soap exceeds a predetermined value, the valve plug 59 will be forced out of the port 60 and soap escapes thereby maintaining the predetermined pressure in the passageway 45 and the conduit 46.

The control head C described above, therefore, has the functions of maintaining a constant back pressure on the soap mass in the device A, and of regulating the pressure and rate of flow of the soap mass issuing from the control head C.

The soap mass being discharged from the conduit 46 may be delivered to any suitable device for further treatment such as, for example, to a form-imparting device in which the soap mass becomes form-retaining as a result of solidification.

From the preceding description of the typical apparatus embodying the present invention, it will be clear that the device is capable of producing in a continuous process soap or other products which have the uniform physical characteristics desired for a marketable product. It will be understood further that one of the primary considerations of the present invention is to provide an apparatus in which soap and other plastic, semi-fluid or fluid products can be worked, agitated, heated or cooled, and, if desired, aerated to change their physical state under uniform conditions of temperature and pressure. Therefore, it will be understood that the illustrated apparatus embodying the present invention is susceptible to considerable change in construction so long as the several elements are capable of maintaining the desired uniform conditions. The above described embodiment of the invention should be considered as illustrative only and not as limiting the scope of the following claims.

I claim:

1. In a device for producing homogeneous compositions, the combination of a pair of parallel meshing screw members, a jacket enclosing said screw members, means for rotating said screw members to cause a mass of material in said jacket to be agitated, worked and conveyed by said screw members from one end of said jacket to the other, a feed hopper communicating with the interior of said jacket adjacent said one end, a pair of rotatable impellers for feeding said material from said hopper into said jacket under pressure, a torque-responsive variable speed transmission for rotating said impellers to feed said material at uniform pressure into said jacket, and a discharge means at said other end of said jacket having means for maintaining a uniform pressure on the material in said jacket, and for discharging the material at constant pressure.

2. In a device for producing homogeneous compositions, the combination of means for agitating and working a mass of said composition comprising a pair of interfitting screw members, a jacket enclosing said members, and means for rotating said screw members to agitate, work and convey the mass from one end of said jacket to the other, a feed hopper at said one end of said jacket, rotary means for feeding the mass from said hopper into said jacket under pressure, a

torque-responsive, variable speed transmission for rotating said feeding means, a discharge means at said other end of said jacket and a constant pressure valve means associated with said discharge means for allowing said mass to escape when the pressure on the mass passing through said discharge means exceeds a predetermined maximum.

3. In a device for producing a composition having agitating means and conveying members enclosed in a jacket, the combination of means for feeding said composition at a constant pressure into said jacket comprising an impeller pump, a torque-responsive, variable speed transmission for actuating said pump and means for discharging said composition under uniform pressure from said jacket.

4. In a device for producing a homogeneous product having a pair of rotary agitating and conveying members enclosed in a jacket, the combination of a rotary impeller pump for feeding material into said jacket; means for actuating said pump at variable speeds comprising a plurality of ratchets connected to said pump, a crankshaft, a plurality of connecting rods actuated by said crankshaft, at least one pawl actuated by each connecting rod to rotate said ratchets, and resilient means coupling said connecting rods to said pawls to permit variable displacement of said pawls in response to variations in the back pressure exerted by the material and said members; and means for discharging the material from said jacket under constant pressure.

5. In a device for treating materials having a pair of rotary agitating and conveying members enclosed in a jacket; the subcombination of a feed hopper, rotary means for feeding material under pressure from said hopper into said jacket, means for actuating said feeding means to feed material into said jacket at a constant uniform pressure comprising ratchets connected to said feeding means, and resilient means for moving ratchets distances inversely proportional to the pressure against which said feeding means operate.

6. In a device for producing homogeneous compositions, the subcombination of a hopper, rotary means for withdrawing a material from said hopper and delivering it under pressure, a drive shaft for rotating said delivering means, a plurality of ratchets fixed to said drive shaft, rocker members on said drive shaft, pawls pivotally mounted on said rocker members engageable with said ratchets, a crankshaft, connecting rods actuated by said crankshaft, and resilient means coupling said rocker members to said connecting rods to permit relative displacement of said connecting rods and said rocker members when the pressure exerted by said delivering means exceeds a predetermined maximum.

7. In a device for treating materials, the subcombination of a hopper, a rotary means for withdrawing a material from said hopper and delivering it under pressure, a drive shaft for rotating said delivering means, a ratchet transmission connected to said drive shaft, a crankshaft and means resiliently connecting said crankshaft and said transmission to permit relative displacement between said drive shaft and said crankshaft when the pressure exerted by said delivering means exceeds a predetermined maximum.

8. In a device for producing homogeneous products having a pair of rotary agitating and con-

veying members enclosed in a jacket; the combination of means for feeding a material into one end of said jacket under constant pressure and means at the other end of said jacket for discharging said material comprising a casing having a discharge outlet and a port adjacent to said outlet, a valve for closing said port and means resiliently urging said valve into said port to prevent said material from escaping through said port unless the pressure in the discharge outlet exceeds a predetermined maximum.

9. In a device for producing homogeneous compositions having a pair of rotary agitating and conveying members enclosed in a jacket; the combination of means for feeding a material into one end of said jacket under constant pressure and means at the other end of said jacket for discharging said material comprising a casing having a discharge outlet and a port adjacent to said outlet, a valve for closing said port and means resiliently urging said valve into said port, said valve being displaceable by pressure to permit said material to escape from said port when the pressure in the discharge outlet exceeds a predetermined maximum, a conduit communicating with said discharge outlet and means for vibrating said conduit to prevent said material from sticking to said conduit.

10. In a device for producing homogeneous compositions having a pair of agitating and conveying elements enclosed in a jacket, the subcombination of a discharge and control head for regulating the flow and pressure of material discharged from said jacket comprising a cylindrical casing having an escape port therein, a discharge branch having a tapering opening communicating with said casing, extending from said casing in spaced relation to said escape port, a first cylindrical valve sleeve rotatable in said casing having a port registerable selectively with said escape port and said tapering opening and a second cylindrical valve sleeve having an elongated arcuate transversely tapered slot therein for regulating the flow of said material through the port in said first valve sleeve.

11. In a device for producing homogeneous compositions having a pair of agitating and conveying elements enclosed in a jacket, the subcombination of a discharge and control head for regulating the flow and pressure of material discharged from said jacket comprising a cylindrical casing having an escape port therein, a discharge branch having a tapering opening communicating with said casing, extending from said casing in spaced relation to said escape port, a first cylindrical valve sleeve rotatable in said casing having a port registerable selectively with said escape port and said tapering opening, a second cylindrical valve sleeve having an elongated arcuate transversely tapered slot therein for regulating the flow of said material through the port in said first valve sleeve, a pressure release port in said discharge branch, a valve for said pressure release port and means resiliently urging the last-mentioned valve into sealing relation with said pressure release port, said resilient means yielding to permit said material to escape from said pressure release port when the pressure on said material exceeds a predetermined maximum.

12. In a device for producing homogeneous compositions, the subcombination of a casing having an outlet branch and an outlet port, a valve plug rotatably mounted therein for communication selectively with said port and said

branch, an escape port in said branch, a valve plug for closing said port and means for urging said plug into said escape port with a predetermined pressure, said means yielding to permit escape of material from said escape port when the pressure on said material exceeds said predetermined pressure.

13. In a device for producing homogeneous compositions, the subcombination of a valve casing, means in said casing for regulating the flow of material therethrough, an outlet branch on said casing, a conduit movably supported on and communicating with said branch, and means for vibrating said conduit relatively to said casing to prevent material from sticking in said conduit. 15

14. In a device for producing homogeneous compositions, a discharge means comprising a valve casing having a discharge branch and an outlet port, a valve sleeve in said casing having an opening therein, a second valve sleeve having an elongated, tapered opening therein, said valve sleeve being concentric, means for adjusting said sleeves relatively to each other to regulate the flow through said openings, and means for rotating said sleeves simultaneously in their adjusted position to register said openings selectively with said outlet port and said discharge branch.

FRED FORREST PEASE.

CERTIFICATE OF CORRECTION.

Patent No. 2,335,306.

November 30, 1943.

FRED FORREST PEASE.

It is hereby certified that error appears in the printed specification of the above numbered patent requiring correction as follows: Page 1, second column, line 15, for "Agitating" read --agitating--; page 2, first column, line 26, for "shaft 16" read --shaft 16a--; page 4, first column, line 10, claim 3, strike out the words "and conveying members"; and that the said Letters Patent should be read with this correction therein that the same may conform to the record of the case in the Patent Office.

Signed and sealed this 18th day of January, A. D. 1944.

(Seal)

Henry Van Arsdale,
Acting Commissioner of Patents
